CLAIM

The ornamental design for a metal bottle as shown and described.

DESCRIPTION

FIG. 1 is a front perspective view of the metal bottle; FIG. 2 is a front elevation view thereof, which is the same as viewed from the left, right, and rear; FIG. 3 is a top plan view thereof; and, FIG. 4 is a bottom plan view thereof.

The broken lines showing environment are for illustrative purposes only and form no part of the claimed design.
